UNITED STATES PATENT OFFICE.

LESLIE W. CLAYBOURN, OF MILWAUKEE, WISCONSIN.

PRINTING-PLATE-SECURING MEANS.

Application filed December 27, 1922. Serial No. 609,287.

To all whom it may concern:

Be it known that I, LESLIE W. CLAYBOURN, a citizen of the United States, residing at Milwaukee, in the county of Milwaukee and State of Wisconsin, have invented certain new and useful Improvements in Printing-Plate-Securing Means, of which the following is a specification.

My invention relates to printing plate securing means arranged for securing a printing plate by means of a hook device, the hook whereof coacts with the edge of the printing plate and the body whereof is shiftable in a groove in a suitable base, which may take the form of a block, plate bed or plate cylinder.

It is the object of my invention to provide new and improved means between the walls of the groove and the body of the hook-member whereby accuracy is increased; further, to provide new and improved means whereby to maintain the hook-device in the groove; further, to provide new and improved means whereby ready movement of the hook device in the groove is obtained; further, to provide new and improved means whereby the moving force applied to the traveling hook-device is distributed along the length thereof; further, to provide new and improved means whereby ready assembling of the parts is obtained; further, to provide new and improved means whereby the number of parts in a device of this character is minimized; and, further, to provide new and improved relations of parts whereby friction between the walls of the groove and the traveling hook-device is minimized.

The invention will be further readily understood from the following description and claims, and from the drawings, in which latter:

Fig. 1 represents a plan view of my improved device in connection with a plate-cylinder, the latter partly broken away.

Fig. 2 is an end elevation of the same.

Fig. 3 is an end elevation of my improved device, with the base in cross-section on the line 3—3 of Fig. 1, and showing the hook-member positioned crosswise of the groove.

Fig. 4 is a side elevation of my improved device, with the hook-member arranged par-

allel with the body, and showing the base in section longitudinally of the groove on the line 4—4 of Fig. 3.

Fig. 5 is a cross-section of the same, taken in the plane of the line 5—5 of Fig. 4.

Fig. 6 is a longitudinal section of my improved device, taken in the plane of the line 6—6 of Fig. 5.

Fig. 7 is a plan view of my improved device, with the base partly broken away, and showing the hook-member extending diagonally of the groove.

Fig. 8 is a horizontal section of the same, taken in the plane of the line 8—8 of Fig. 3.

Fig. 9 is a similar view, showing the wing member held longitudinally of the groove.

Fig. 10 is a horizontal section of my improved device, taken in the plane of the line 10—10 of Fig. 4.

Fig. 11 is a perspective view of the various parts of my improved device in separated relation.

Fig. 12 is a side elevation of my improved traveling hook device.

Fig. 13 is an end elevation of the same.

Fig. 14 is a perspective view of my improved operating key; and,

Fig. 15 is a detail view in cross-section, on the line 15—15 of Fig. 11.

I have exemplified my invention as applied to a printing-plate cylinder, although the same may be applied to a flat bed or to blocks which are assembled to make up a form from which to print.

A suitable plate-cylinder is exemplified at 21. It is provided with grooves 22, which are helically arranged about the cylinder in the cylindrical plate-supporting surface 23 of the cylinder.

The side walls 24 of the grooves are preferably adjacent, their outer ends provided with ledges 25 which project toward each other. These ledges are exemplified as 95 formed by means of slots 26 in the respective side walls of the grooves.

The inner or bottom ends of the grooves are provided with opposite slots 27. A rack-bar 28, having a rack 29 thereon, is in the inner end of the groove, the side edges of the rack-bar being received in the inner side slots 27.

The rack-bar forms a bottom wall for

the groove. The teeth of the rack are shown flush with the top of the rack-bar.

In the form shown, the ledges 25, the slots 26 and 27, the rack-bar 28, the rack 29, and the side walls and the bottom wall of the groove are helical, and have the same lead. The helices of the outer portions of the groove are described on cylindrical planes of greater diameter than the diameters of 10 the cylindrical planes on which the helices of the inner portions of the grooves are described. The outer portions of the groove have therefore a greater helix angle than the inner portions. The helix angle increases toward the outer end of the groove, or, as the groove approaches the cylindrical plate-supporting surface of the plate-cylinder. As a consequence there is a slant or twist to the side walls of the groove, from 20 bottom to top of the groove, as shown at 30, in the length of the traveling hook device hereinafter described.

A traveling hook device 31 is located in the groove, a suitable number of these hook 25 devices for the grooves being provided so that a printing plate, exemplified at 32, or any suitable number of printing plates, may be secured to the plate-support, exemplified as the cylinder 21. The printing plate is 30 exemplified as a curved printing plate, having a printing surface 33, and edges 34 suitably formed, as by beveling the same, for being held by the hook device.

Flat plates may also be held by my improved device, in which case a plate bed or flat blocks are employed, having diagonal grooves therein, in which the correspondingly formed hook devices are received.

The traveling hook device comprises a 40 body 37 and a hook-member 38, which latter, in the present instance, comprises a plate-holding hook 39. A wing-member comprising wings 40 is provided. There is a shank 41 between the hook and the wings, forming 45 a journal in a bearing 42 in the body. The combined hook and wing member is shown as an integral structure and preferably has a central bore 45, which forms a bearing for the hub 46 of a bevel-gear 47, the head 48 50 of the bevel-gear being journaled in a bearing 49 and provided with a shoulder 50, which coacts with the wing-member, to limit upward movement between the bevel-gear and the combined hook and wing-member.

55 The bevel-gear is provided with turning means, for instance, a socket 52 of polygonal cross-section, which has an opening 53 through the bottom of the bevel-gear shown as a square socket, for receiving the correspondingly formed entering end 54 of an operating key 55, having a knurled operating end 56 and a handle 57, for rotating the same and thereby rotating the bevel-gear. The knurled operating end is for rapid spinning of the bevel-gear, and the handle

for slower rotation of the same, for instance, when seating the hook on the printing plate. The handle end of the operating key is provided with a cross-slot 58, arranged to be received over the hook 39, for turning the combined hook and wing-member, the side walls of the slot engaging the respective front and rear edges of the hook. The combined hook and wing-member may also be turned by the fingers.

75 The hook device may be inserted in any portion of any of the grooves adjacent to the edge of the printing plate with which it is to coact, and the gearing employed for finer adjustment and for registering effect.

80 In the form shown, the wings have rounded faces 61, the combined wings forming a wing-member having a face in the form preferably of a truncated frusto-cone. These rounded faces are shown as the upper faces 85 of the wings, and are arranged to coact with the lower faces of the ledges. These lower faces are helical lengthwise of the ledges, and in cross-section are preferably formed drooping toward their outer ends, preferably 90 of cross-sectional form to correspond with the conical faces of the wings, shown at the top of the wings.

95 The upper faces of the wings and the lower faces of the ledges coact to retain the traveling hook device within the grooves, to prevent accidental movement of the hook devices out of the grooves and to hold the hook devices to the plate-cylinder, so that the printing plate may be firmly secured to 100 the plate-cylinder by means of the hook devices. The contact between the coacting faces of the wings and the ledges is preferably such as to form a line-contact between the upper faces of the wings and the lower 105 faces of the ledges, to provide ready movement between the wings and the ledges when turning the wings, and also to relieve friction and provide ready movement of the wings lengthwise of the ledges. The line-contact is obtained by having the upper face 110 of the wing, which is of greater curvature, coact with the helical lower face of the ledge, which is of less curvature, lengthwise of the groove, than the curvature of the upper face 115 of the wing.

120 The body is provided with a cavity 64, the lower face of whose upper wall 65 is preferably formed to correspond with the curvature of the upper faces of the wings received therein. This cavity is preferably adjacent to the top of the body for forming a shallow roof 66 above the cavity.

125 The wing-member has abbreviated or truncated sides 67, so as to form the wing-member of greater length than width, the wing-member being positioned lengthwise of the body and groove and preferably within the body when it is desired to insert a traveling hook device into or out of a 130

groove. The side walls of the cavity in the body are provided with slots 68, through which the wings extend when the wing-member is rotated to have the wings received under the ledges for holding the hook device to the cylinder.

Means are provided to preferably automatically hold the wings under the ledges, so as to avoid the dropping of the hook device or accidental removal thereof out of the groove, and for holding the hook 39 in position to engage the right angle edges of a printing plate, whereby the hooks extend substantially diagonally crosswise of the grooves. The hooks preferably extend parallel with the wings.

A resilient holding means is provided, which comprises a plunger 70, shown as a ball and a spring 71, which is arranged to normally urge the plunger toward the wing. The body is provided with a recess 72, in which the plug and the spring are received. The recess is provided with an apertured end wall 73, which holds the ball in the recess and through which the ball projects into contact with the wing-member.

The plunger is arranged to contact the rounded edge of the wing to maintain the wing-member in any angular position or parallel with the body, in which the wing-member may be manually placed, or to contact the truncated edge of the wing-member. When the plunger is caused to contact the truncated edge, in which relation the projecting edges of the wings are definitely located under the ledges 25, additional turning force must be applied to the combined hook and wing-member to turn the same, for the reason that the corner between the truncated edge and the rounded edge of the wing-member must first force back the ball resisted by the pressure of the spring before the rounded edge will ride along the plunger. The wing-member may be rotated to present either wing to the plunger.

The combined hook and wing-member may be manually turned by means of the hook against the resistance of the spring in either direction, so as to be parallel with the body, for removal of the hook device or for placement in any desired position in one of the grooves, (see Figs. 4, 5, 6, 9, 10, 12 and 13), and after insertion in one of the grooves, the combined hook and wing-member may be turned so that the hook will contact with the edge of a printing plate on the support, (see Figs. 1, 3, 7 and 8), it being understood that the edges of the printing plates may extend in different directions, for instance as shown in Fig. 1 of the drawings. Pressure of the plunger against the edge of the wing maintains the wing-member in adjusted position and maintains the wing-member crosswise of the groove under the ledges. The slightest turn of the wing-

member places the wings under the ledges, and the spring-pressed plunger holds the wings in that position, to prevent accidental removal or falling out of the traveling hook device when out of contact with a printing plate.

The hook is provided with a plate-engaging face 75, preferably of substantial length, arranged to engage the beveled edge 34 of the printing plate, and to arrange itself lengthwise of the beveled edge of the printing plate, regardless of the direction in which this beveled edge may extend, due to the force applied in moving the hook device toward the printing plate, the plunger yielding to this force in case such movement of the hook toward the printing plate causes rotation of the hook on its upright axis.

A shaft 80 is journaled in the body in end-bearings 81 and a median bearing 82, preferably below the wing-member. Helical gears 83, 84, are fixed to the shaft, there being preferably a pair of these helical gears, spaced apart, with the upright axis 90 of the bevel-gear 47 between them. A bevel-gear 85 is fixed to this shaft between the helical gears 83, 84, and meshes with the bevel-gear 47. The helical gears form worm gears which mesh with the rack 29, 95 which is shown of worm form.

This arrangement distributes the forces applied for moving the traveling hook device, lengthwise of the hook device, and aids in ease of movement of the hook device lengthwise of the groove, while shifting the hook device either forward or back. In this arrangement the operating means for causing shifting of the hook device in the groove is located on an upright axis between the pair of helical gears, and the wings contact the ledges at points between the outer ends of the pair of helical gears, so as to hold both of the helical gears in full meshing relation with the rack.

To further aid in the ease of movement of the traveling hook device and the distribution of the moving forces therefor, the lower face of the body is provided with a riding face 87 which coacts with the upper face of the rack-bar, as shown in Figs. 3 to 6 inclusive, this riding face being preferably helical when the grooves are formed in a plate cylinder, as exemplified.

The tooth-spaces in the rack are shown cut into the rack-bar, and the lower face of the body as riding on the upper face of the rack-bar and teeth.

The form of the lower face of the body which I prefer when used in a plate-cylinder, is shown in Figs. 3, 5, 11, 12 and 13 as helical. It may be produced by grinding by means of a grinding wheel having a cylindrical grinding face of a diameter preferably not greater than twice the radius of the

plate-cylinder from its axis to the closest point in the riding surface of the rack-bar, the axis of the grinding wheel being presented at an angle to the longitudinal axis 5 of the body equal to the helix angle of the bottom of the groove, that is, of the riding surface on the rack-bar.

In order to accommodate the body to the slanting or twisted side walls of the helical 10 grooves and at the same time provide for ready movement of the body lengthwise of the groove, I provide the side walls of the body with slanting faces 91, 92, extending lengthwise of the body and at diagonally opposite corners, providing clearance for a groove formed on a left-hand spiral, as shown. The opposite ends of the side walls of the body are preferably provided with slanting faces 93, 94, extending lengthwise 15 of the body and at diagonally opposite corners, providing clearance for a groove formed on a right-hand spiral, or for additional clearance.

The lower edges of the side walls of the 20 body are preferably provided with parallel positioning faces 95, 96, for contacting the lower ends of the side walls of the groove, the slanting faces 91, 92, or 93, 94, providing clearance in the body for the twisting 30 of the side walls 24 of the groove above said lower edges. The side walls of the body are provided with positioning faces 97, 98, extending above said lower positioning faces 95, 96, and between the respective clearance 35 spaces formed by the slanting faces 91, 93, and 92, 94. The body of the traveling hook-member is therefore preferably provided with lower side positioning faces and with median upright positioning faces, in substantially 40 the form of an inverted T, to maintain the body parallel with the groove.

The upper face of the body has slanting faces 99, 100, which slant downwardly and outwardly toward diagonally opposite corners of the body to provide clearance so that the top of the body does not extend above the groove when a helical groove is employed.

I preferably make the traveling hook device in as few parts as possible, and for this reason I prefer to form the hook-member and the wing-member as an integral structure, having the journal for rotatingly supporting the same thereon, and form the shaft, the pair of helical gears and the bevel-gear thereon as an integral structure, a further integral structure being the upright bevel-gear and its operating shank or hub, making a total of three major moving parts in 60 the body.

In order to provide for readily assembling these parts in the body, and to enable few moving parts to be employed, I form the body in sections, exemplified as two sections, 65 106, 107, the parting plane 108 between the

sections being substantially coincident with the plane in which the axes of rotation of the combined hook and wing-member and the shaft are located. Each of the sections is provided with the bearing-halves for the 70 shaft, for the shank or journal of the combined hook and wing-member, and for the head of the upright bevel-gear, the sections also being provided with the respective halves of the cavities 109 for the helical 75 gears and the horizontal bevel-gear 85.

The sections are preferably duplicates of each other and are interchangeable, so that any section may be used at one side or the other side of the body. Each section is also 80 preferably provided with one of the recesses 72, so that the plunger and its spring may be placed at either end of the wing-member.

The sides of these recesses are open at the meeting plane between the sections, as shown 85 at 111, so that the plunger and spring may be assembled in the recess through this open side, and the form of the recess is preferably such that the ball and spring will remain in the recess without holding the same after 90 the same is inserted in the recess, as by having one end of the recess square, as shown at 112, to hold one end of the spring, and having the other end of the recess provided with the apertured end wall 73 to encompass the 95 ball.

Contact between the ends of the helical 100 gears and the end walls of the cavities therefor in the body-sections, positions the shaft, the helical gears and the lower bevel-gear axially, for causing proper and close meshing relation between the bevel-gears and between the helical gears and the rack. The shaft, the helical gears and the bevel-gears are preferably located below the wing-member. 105

Shoulder-screws 114 are arranged to firmly secure the body-sections together and to properly relatively locate the same, the heads of the screws being preferably received in holes 115 in the body-sections. There are preferably two of these screws employed, extending in opposite directions crosswise at the respective ends of the body. The head-end of each screw is journaled in 110 one body-section and its threaded end is threaded into the other body-section at the respective ends of the body.

My improved device is simple in construction, durable, and of few parts, and the traveling hook device is readily and accurately movable lengthwise of the groove for providing a simple, economical, strong and durable registering hook device for printing plates. 120

Having thus fully described my invention, what I claim as new, and desire to secure by Letters Patent, is:

1. In a traveling hook device, the combination of a body having a cavity extend- 125 130

- ing throughout the width of said body and provided with slots opening into said cavity from the side walls of said body, and a rotatable combined hook and wing-member comprising wings in said cavity arranged to project through said slots. 5
2. In a traveling hook device, the combination of a body having a cavity in its top throughout the width of said body and provided with slots opening into said cavity from the side walls of said body, and forming a shallow roof for said cavity at the upper end of said body, and a combined hook and wing-member comprising wings 10 and having a shank between the hook and wings thereof journaled in said roof, said member rotatable for locating said wings lengthwise of said body or crosswise of said body and extending through said slots. 15
3. In a traveling hook device, the combination of a body having a cavity in its top throughout the width of said body and provided with slots opening into said cavity from the side walls of said body and forming a shallow roof for said cavity at the upper end of said body, a combined hook and wing-member comprising wings and having a shank between the hook and wings thereof journaled in said roof, said member 20 rotatable for locating said wings lengthwise of said body or crosswise of said body and extending through said slots, and means resiliently holding said wings crosswise of said body. 25
4. In a traveling hook device, the combination of a body having a cavity extending throughout the width of said body and provided with slots opening into said cavity from the side walls of said body, a rotatable wing-member comprising wings in said cavity arranged to project through said slots, and gearing means on said body causing 30 travel of said body. 35
5. In a traveling hook device, the combination of a body having a cavity extending throughout the width of said body and provided with slots opening into said cavity from the side walls of said body, a rotatable wing-member comprising wings in said cavity arranged to project through said slots, and a gear under said wing-member arranged for receiving an operating tool at the top of said wing-member. 45
6. In a traveling hook device, the combination of a body, a combined hook and wing-member journaled in the upper portion of said body, gearing journaled in the lower portion of said body under said combined hook and wing-member, and gearing between said combined hook and wing-member and said first-named gearing. 50
7. In a traveling hook device, the combination of a body, a wing-member for coaction with a base, said wing-member journaled in said body on an upright axis, and of said body on an upright axis, and of said body, a bevel-gear between said 55
- gearing in said body under said wing-member for coaction with said base. 8. In a traveling hook device, the combination of a body, a wing-member for coaction with a base, said wing-member journaled in said body on an upright axis, gearing in said body under said wing-member for coaction with said base, and means for operating said gearing extending through 60 said wing-member. 70
9. In a traveling hook device, the combination of a body, a combined hook and wing-member comprising a hollow journal, a bearing therefor in the upper portion of said body, and gearing for coaction with a base located in the lower portion of said body and comprising a gear with an upright axis having a hub journaled in said bore of said combined hook and wing-member. 65
10. In a traveling hook device, the combination of a body, a combined hook and wing-member comprising a hollow journal, a bearing therefor in the upper portion of said body, and gearing for coaction with a base located in the lower portion of said body and comprising a gear with an upright axis having a hub journaled in said bore of said combined hook and wing-member, and said hub formed to receive an operating tool for rotating said gearing. 75
11. In a traveling hook device, the combination of a body, a combined hook and wing-member journaled in the upper portion of said body on an upright axis and provided with a bore, a shaft journaled in the lower portion of said body lengthwise of the direction of travel of said body, spaced-apart gears thereon for coaction with a base, an intermediate gear on said shaft between said first-named gears, and a gear having an upright axis meshing with said last-named gear and journaled in said bore. 80
12. In a printing plate securing means, the combination of a base provided with a groove, a rack therein, and a traveling hook device comprising a body, spaced-apart gears journaled therein coacting with said rack, said gears spaced apart in the direction of travel of said body, gearing for operating said spaced-apart gears intermediate between said spaced-apart gears and comprising an upright gear, means whereby to rotate said upright gear, and a rotatable hook-member, said upright gear and said rotatable hook-member having coincident axes of rotation in said body. 85
13. In a printing plate securing means, the combination of a base provided with a groove, a rack on the lower wall of said groove, a traveling hook device comprising a body, spaced-apart helical gears journaled in said body and projecting downwardly into coaction with said rack, said helical gears spaced apart in the direction of travel 90
- of said body, a bevel-gear between said 125

spaced-apart gears for operating the same, and an upright bevel-gear meshing with the latter.

14. A traveling hook device comprising a rotatable wing-member comprising wings, said wings provided with faces which are a substantial frusto-cone, a shaft, spaced-apart helical gears on said shaft, a bevel-gear on said shaft, an upright bevel-gear meshing therewith, the axes of rotation of said rotatable wing-member, said upright bevel-gear and said shaft being in substantially the same upright plane, and a body comprising a pair of sections having a parting line in substantially the plane of said axes of rotation, each of said sections having bearings and recesses therein which mate each other when assembled and accommodate said parts mentioned.
15. A traveling hook device comprising a rotatable hook and wing-member having a journal-shank between the hook and wings thereof, a shaft having an axis of rotation substantially at right angles to the axis of rotation of said combined hook and wing-member, spaced-apart helical gears on said shaft, a bevel-gear on said shaft between said spaced-apart helical gears, an upright bevel-gear having an axis of rotation substantially coincident with the axis of rotation of said combined hook and wing-member, said bevel-gears being in mesh with each other, and a body comprising mating sections having a parting line therebetween in substantially the plane of said axes of rotation and respectively provided with bearings in which said shaft and said shank are journaled and with recesses in which said spaced-apart helical gears are received.
16. A traveling hook device comprising a combined hook and wing-member provided with a bore and a journal-shank between the hook and wings thereof, a bevel-gear journaled in said bore on an upright axis, a shaft having an axis of rotation at substantially right angles to the axes of rotation of said bevel-gear and said hook and wing-member, spaced apart helical gears on said shaft, a bevel-gear on said shaft between said helical gears meshing with said first-named bevel-gear, and a body comprising sections having a parting line between them in substantially the plane in which said axes of rotation are located and respectively provided with bearing-halves for said shank, said first-named bevel-gear and said shaft and with mating recesses in which said spaced-apart helical gears are located.
17. A traveling hook device comprising a combined hook and wing-member provided with a bore and a journal-shank between the hook and wings thereof, a bevel-gear journaled in said bore on an upright axis, a shaft having an axis of rotation at substantially right angles to the axes of rotation of said bevel-gear and said hook and wing-member, spaced apart helical gears on said shaft, a bevel-gear on said shaft between said helical gears meshing with said first-named bevel-gear, and a body comprising sections having a parting line between them in substantially the plane in which said axes of rotation are located and respectively provided with bearing-halves for said shank, said first-named bevel-gear and said shaft and with mating recesses in which said spaced-apart helical gears are located.
18. A traveling hook device comprising a combined hook and wing-member, an upright bevel-gear journaled therein, a horizontal shaft, spaced-apart helical gears thereon, a bevel-gear on said shaft meshing with said upright bevel-gear between said spaced-apart helical gears, a spring-pressed plunger coacting with said wing-member, and a body having recesses for said aforementioned elements and compressing duplicate sections having a mating plane between them intersecting said recesses.
19. In printing plate securing means, the combination of a base provided with a groove having a ledge, a traveling hook device in said groove, a retaining wing thereon, and means whereby to shift said wing laterally for location thereof under said ledge, the upper face of said wing being rounded and arranged to contact the lower face of said ledge with a line-contact to retain said traveling hook device in said groove.
20. In printing plate securing means, the combination of a base provided with a helical groove having a helical ledge provided with an under outwardly drooping helical contact-face, a traveling hook device in said groove, and a rotatable retaining wing thereon provided with an upper rounded contact-face contacting said under helical contact-face.
21. In printing plate securing means, the combination of a base provided with a helical groove having a helical ledge at each side thereof, said ledges presented toward each other and provided with under outwardly drooping helical contact-faces, a traveling hook device in said groove, and a wing-member rotatable in said hook device, said rotatable wing-member provided with wings arranged to project laterally from the respective sides of said traveling hook device, and said wings having rounded upper faces coacting with said under contact-faces, whereby line-contacts are had between said contact-faces.
22. In printing plate securing means, the combination of a base provided with a helical groove having a helical ledge at each side thereof, said ledges presented toward each other and provided with under outwardly

tion of said bevel-gear and said hook and wing-member, spaced-apart helical gears on said shaft, a bevel-gear on said shaft between said helical gears meshing with said first-named bevel gear, a body comprising sections having a parting line between them in substantially the plane in which said axes of rotation are located and respectively provided with bearing-halves for said shank, said first-named bevel-gear and said shaft, and with mating recesses in which said spaced-apart helical gears are located, and means for securing said sections together.

- drooping helical contact-faces, a traveling hook device in said groove comprising a rotatable hook member, wings movable therewith, and means to arrest said wings in a plurality of rotative positions, said wings having rounded upper contact-faces coacting with said under contact-faces, whereby line-contacts are had between said respective wings and said respective under contact-faces in said respective wing-positions. 5
23. In a printing plate securing means, the combination of a traveling hook device comprising a retaining wing having an upper rounded face, and a base provided with a groove in which said traveling hook device is received, said groove having a ledge provided with a concave face of less curvature lengthwise of said groove than the curvature of said rounded face, whereby coaction between said faces is obtained with a line-contact. 15
24. In printing plate securing means, the combination of a base provided with a groove having a ledge, a traveling hook device in said groove comprising a body, a rotatable hook-member rotatable in said body, a retaining wing rotatable with said rotatable hook-member, and a resiliently actuated plunger to releasably hold said retaining wing crosswise of said groove. 20
25. In printing plate securing means, the combination of a base provided with a groove having ledges presented toward each other, a traveling hook-device comprising a body in said groove and a wing-member in said body, said wing-member provided with oppositely extending wings arranged to be placed lengthwise of said body for moving said body into and out of said groove and crosswise of said body for placing said wings under said ledges, and resilient means to hold said wings under said ledges. 25
26. In printing plate securing means, the combination of a base provided with a groove having ledges presented toward each other, a traveling hook device comprising a body in said groove and a wing-member in said body, said wing-member provided with oppositely extending wings arranged to be placed lengthwise of said body for moving said body into and out of said groove and crosswise of said body for placing said wings under said ledges, said wing-member having truncated edges, and resilient means between said body and said wing-member coacting with said truncated edges whereby to move said wings obstructingly under said ledges to maintain said body in said groove. 30
27. In printing plate securing means, the combination of a base provided with a groove having ledges projecting toward each other, a traveling hook device comprising a body in said groove and a rotatable combined hook and wing-member comprising wings and arranged whereby to position said wings within said body for movement of said body into and out of said groove and crosswise of said body, said wing-member provided with a rounded edge and with a truncated edge, and resilient means coacting with said edges to maintain said wing-member in adjusted positions. 35
28. In printing plate securing means, the combination of a base provided with a helical groove and a traveling hook device in said groove, said traveling hook device comprising a body having side recesses at its outer ends to provide clearances for the side walls of said helical grooves, and guiding means at its inner end guided by said side walls. 40
29. In a printing plate securing means, the combination of a plate-cylinder provided with helical grooves respectively having helical side walls and a helical bottom wall, helical ledges presented toward each other at the outer ends of said side walls, and a traveling hook device comprising a body in said groove provided with a bottom having a helical riding face coacting with said helical bottom wall, and a rotatable wing-member rotatable in said body provided with wings having a rounded upper contact-face arranged to be received under said ledges. 45
30. In a printing plate securing means, the combination of a base provided with a groove having parallel side walls, an outwardly laterally extending slot at the bottom of each of said side walls, and a laterally outwardly extending slot adjacent the top of each of said side walls for forming oppositely projecting ledges at the top of said groove projecting toward each other, a rack-bar in the bottom of said groove whose side edges are located in said first-named slots, a traveling hook device in said groove comprising a body, a worm rotatable therein and coacting with the rack of said rack-bar, a combined hook and wing-member comprising oppositely extending wings, and means whereby to rotate said last-named member to locate the wings thereof in said second-named slots under said ledges. 50
31. A traveling hook device comprising a body the upper portions of whose diagonally opposite ends are recessed at their sides. 55
32. A traveling hook device comprising a body the upper portions of whose diagonally opposite ends are recessed at their sides and whose bottom is provided with an upward median recess. 60
33. A traveling hook device comprising a body the upper portions of whose diagonally opposite ends are recessed at their sides and whose upper face slants in opposite diagonal directions from the middle portion of said body. 65

34. A traveling hook device comprising a body the upper portions of whose diagonally opposite ends are recessed at their sides, and retaining wings at the median upper portion of said body. 30
35. A traveling hook device comprising a body the upper portions of whose diagonally opposite ends are recessed at their sides and whose bottom is provided with an upward median recess, and retaining wings at the upper median portion of said body. 35
36. A traveling hook device comprising a body whose side walls are provided with contact-faces substantially in the form of an inverted T. 40
37. A traveling hook device comprising a body whose side walls are provided with contact-faces substantially in the form of an inverted T, and whose bottom face is upwardly recessed in its median portion. 45
38. In a printing plate securing means, the combination of a traveling hook device comprising a body, and a base provided with a helical groove whose side walls have the same lead from top to bottom, the helix angle of said side walls increasing from bottom to top, whereby said side walls have a twist in the length of said body received in 25

said groove, and the upper portions of the sides of the diagonally opposite ends of said body being reduced to form clearance spaces for said side walls. 30

39. In a printing plate securing means, the combination of a traveling hook device comprising a body, and a base provided with a helical groove whose side walls have the same lead from top to bottom, the helix angle of said side walls increasing from bottom to top, whereby said side walls have a twist in the length of said body received in 40 said groove, the bottom of said groove being a helix described on a cylinder, the upper portions of the sides of the diagonally opposite ends of said body being reduced to form clearance spaces for said side walls, and the bottom face of said body being recessed at its middle portion to accommodate said bottom. 45

In testimony whereof, I have hereunto signed my name in the presence of two subscribing witnesses. 50

LESLIE W. CLAYBOURN.
